FIG. 1

FIG. 1

FIG. 2

FIG. 1

FIG. 3

FIGURE 1 is a front elevational view of the combined tube and closure showing my new design;

FIGURE 2 is a front perspective view of the tube with the closure removed; and

FIGURE 3 is a bottom perspective view of the closure. From the rear the tube appears the same as from the front with the exception that the tube is plain and without ornamentation above the checkerboard pattern.

I claim:

The ornamental design for a combined tube and closure, as shown and described.
